UNITED STATES PATENT OFFICE.

MERRICK A. MIHILLS, DECEASED, LATE OF HIGHLAND PARK, ILLINOIS, BY EDWARD W. McDERMOTT, ADMINISTRATOR, OF WAUKEGAN, ILLINOIS, ASSIGNOR TO MINA A. MIHILLS, OF HIGHLAND PARK, ILLINOIS.

DESIGN FOR A RAZOR-STRAP HOLDER.

47,386.

Specification for Design.

Patented May 25, 1915.

Application filed February 19, 1915. Serial No. 9,457. Term of patent 14 years.

To all whom it may concern:

Be it known that MERRICK A. MIHILLS, deceased, late a citizen of the United States, residing at Highland Park, county of Lake, and State of Illinois, invented a new, original, and ornamental Design for a Razor-Strap Holder, of which the following is a specification, reference being had to the accompanying drawing, forming part thereof.

The figure is a perspective view of the razor strap holder, showing my new design.

Copies of this patent may be obtained for five cents each, by addressing the "Commissioner of Patents, Washington, D. C."

I claim:

The ornamental design for a razor strap holder, as shown.

In testimony whereof, I affix my signature in the presence of two witnesses.

EDWARD W. McDERMOTT,
Administrator of the estate of Merrick A.
Mihills, deceased.

Witnesses:

W. M. L. FARMER,
W. F. WEISS.
